CLAIM

The ornamental design for a dental illumination device, as shown and described.

DESCRIPTION

FIG. 1 is a top perspective view of a dental illumination device according to the present invention;

FIG. 2 is a bottom perspective view of the dental illumination device;

FIG. 3 is a top view of the dental illumination device;

FIG. 4 is a bottom view of the dental illumination device;

FIG. 5 is a side view of the dental illumination device;

FIG. 6 is a front view of the dental illumination device; and,

FIG. 7 is a rear view of the dental illumination device.

The broken lines shown in the figures are for illustrative purposes only and form no part of the claimed design.
